UNITED STATES PATENT OFFICE.

ALFRED DOLGE, OF LOS ANGELES, CALIFORNIA.

PROCESS OF MAKING SOUNDING-BOARDS FOR PIANOS.

No. 879,373.

Specification of Letters Patent.

Patented Feb. 18, 1908.

Application filed October 29, 1903. Serial No. 179,073.

To all whom it may concern:

Be it known that I, ALFRED DOLGE, a citizen of the United States, residing at Los Angeles, in the county of Los Angeles, State of California, have invented and discovered a new and useful Improvement in the Process of Making Sounding-Boards for Pianos; and I do hereby declare the following to be a full, clear, and exact description of the invention, such as will enable others skilled in the art to which it appertains to make and use the same.

This invention relates to the process of making sounding boards for pianos and other musical instruments, and it has for its objects to render the process of manufacture more expeditious, to lessen the cost of production and to produce superior sounding boards than have heretofore been placed upon the market.

The saving of time, labor, cost of manufacturing and to produce sounding boards having greater capacity for conducting sound waves than have hitherto been used, are the factors for consideration to be hereinafter more particularly set forth in the description of my improved process, reference being made to the accompanying drawings, to the figures and reference numerals, letters and characters marked thereon; and the invention consists essentially in the steps and series of steps enumerated hereinafter and fully described in the specification, shown upon the drawings appended hereto and specifically pointed out in the claims made a part hereof.

I attain these objects by the series of steps delineated in the specification and set forth in the accompanying claims and illustrated upon the drawings, in which—

Figure 1, is a plan view of one of the boards the ends thereof broken away, from which the strips comprising the sounding board is made up; Fig. 2, is a plan view of one of the strips mitered at each end, cut from the board shown upon Fig. 1, of the drawing; Fig. 3, is a plan view of a series of the mitered strips shown upon Fig. 2 glued, assembled and pressed together; and, Fig. 4 is a plan view of a finished sounding board made by my improved process.

The lumber used in carrying out my improved process, is cut from trees that grow to prodigious heights free from natural defects hereinafter to be mentioned and the trunks thereof are of marvelous lengths.

The bodies of these trees are economically cut into logs which are sawed into boards of certain dimensions and the boards dried by the natural process in an atmosphere comparatively free from moisture, by the heat of the sun. The said boards, 2, are cut into strips, 3, shown upon Fig. 2 of the drawing of proper lengths and these strips, 3, are assembled in sufficient numbers as shown upon Fig. 4 of the drawing to manufacture sounding boards economically. These strips 3, cut from the boards, 2, are planed and dressed, and the ends, 6, 6, thereof are mitered as shown upon Fig. 2 of the drawing. The said strips, 3, mitered at each end are glued upon their edges, assembled and firmly pressed together as shown upon Fig. 3 of the drawing, sufficient in number to make the board shown upon Fig. 3 of the drawing the width required by manufacturers of pianos or other musical instruments. After the requisite number of the said mitered strips 3, 3, are glued, the mitered ends, 6, 6, of the strips are arranged in parallel line forming a rhomboidal board; and are pressed together and dried, as illustrated upon Fig. 3, of the drawing. The rhomboidal board of assembled strips is now cut upon the diagonal line x—x, as shown upon Fig. 3, of the drawing forming two sections. The said two sections, triangular in shape are now placed in position as illustrated upon Fig. 4 of the drawing so as to bring the edges cut upon the line x—x, of Fig. 3, upon the outer and opposite edges of the sounding board, 4, shown upon Fig. 4 of the drawing,—the outer and opposite edges 77 of the rhomboidal board illustrated upon Fig. 3 of the drawing having been previously covered with glue are assembled, pressed together and dried forming the completed sounding board, shown upon Fig. 4 of the drawing.

The continuity of the fibers in each section of the strip of lumber composing the sounding board has great effect in increasing the conduction of the waves of sound and in giving quality to the sound so much desired by manufacturers of musical instruments.

I have discovered from long experience in the manufacture of sounding boards for pianos and other musical instruments, that there is great waste of material employed in their construction, although the lumber be carefully and skilfully selected from the best assorted material now to be found in the markets. This waste arises from natural

defects inherent in the lumber, particularly "knots" abundantly found in boards sawed from trees having short bodies which grow in almost every quarter of the globe. From these short bodied trees the boards are sawed and the best ones are selected from which the best sounding boards now used by the most skilful manufacturers, are made. I have also discovered that there are other natural defects incident to the growth of trees from which boards are sawed, out of which the best sounding boards for pianos and other musical instruments now in use, are manufactured. These defects are "twists" or contortions of the woody fibers composing the lumber selected. These "twists" or contortions of the woody fiber are invariably found in the best and most select lumber cut from trees that grow in regions or sections of country frequently visited by cyclones, tornadoes and wind-storms. I have furthermore discovered that trees from which lumber is sawed that grow along and in close proximity to the shore of the Pacific Ocean in a climate and in an atmosphere where cyclones, tornadoes and wind-storms never prevail, reach prodigious heights without having a single branch or limb springing from the trunks thereof. These trees when cut into lumber furnish boards and strips thereof for sounding boards, free from "knots" and "twists" and other natural defects which greatly facilitate the manufacture of sounding boards for pianos and other musical instruments, of a superior character to boards made from lumber heretofore employed.

In the semi-tropical climate of Southern California and other climates similar thereto, where the atmosphere contains comparatively little moisture, I have discovered by experience, that lumber dried or "seasoned" by the sunshine is of better quality than lumber dried by artificial means in climates containing a great amount of moisture. Lumber dried by the natural process in the sun also reduces the cost of producing sounding boards made from lumber "seasoned" by artificial means. Besides this, another item in lessening the cost of producing sounding boards for pianos and other musical instruments, I have also considered, and that is, the southern section of the State of California is in close proximity to the great tree-growing sections of the Pacific Coast States herein above referred to.

In using lumber of the character above referred to grown and produced from trees indigenous to the regions and sections of country above mentioned and "seasoned" and dried by the natural process of sunshine, I have found that there is a great saving of time, labor and in the cost of production of sounding boards for pianos and other musical instruments, as well as producing sounding

boards of a superior quality to sounding boards hitherto made and now found in the markets.

The operation of this, my improved process, will be readily understood from the foregoing description when taken in connection with the drawing hereto appended.

It is obvious that many variations and changes in the details of the steps of my improved process would readily suggest themselves to persons skilled in the art of making sounding boards for pianos and other musical instruments and still be within the spirit and scope of my invention.

I do not desire to confine this invention to the specific steps herein shown and described in the specification and claims and the right is reserved to make all changes in and modifications of the same as come within the spirit of this invention.

Having described my invention, what I do claim and desire to secure by Letters Patent, is—

1. The process of manufacturing sounding boards for pianos and other musical instruments consisting in cutting the strips of lumber; cutting at an angle the opposite ends of the strips along parallel lines gluing and assembling the said strips in numbers sufficient to form the width of the sounding boards to be made along the angular ends to form a rhomboid; pressing the glued and assembled strips together; cutting the rhomboid on the short diagonal line connecting the opposite corners thereof; and gluing and pressing together the outer opposite edges of the assembled strips.

2. The process of manufacturing sounding boards consisting of mitering the opposite ends of strips of lumber along parallel lines; gluing and assembling the said strips to form a rhomboid, pressing the adjacent edges of the strips together and drying the same; cutting diagonally across the assembled strips; and gluing, assembling and pressing together the outer parallel edges of the strips along parallel lines, and drying the same.

3. The process of manufacturing sounding boards, consisting in mitering the ends of strips of lumber along parallel lines; gluing, assembling and pressing the edges of the strips together to form a rhomboid; cutting diagonally across the assembled strips; and gluing and pressing together the two outer parallel edges of the assembled strips.

4. The process of manufacturing sounding boards consisting in cutting strips into the length required; mitering the opposite ends of the strips along parallel lines; gluing, assembling in parallel lines the said strips to form a rhomboid, pressing and drying the assembled adjacent edges of the strips; cutting diagonally across the assembled strips; and gluing and pressing together the outer parallel edges of the strips.

5. The process of manufacturing sounding boards consisting in cutting strips into lengths, cutting at an angle the opposite ends of the strips along parallel lines; gluing, assembling and adjusting in alinement to each other the cut angular ends of the strips and pressing together the adjacent edges of the strips parallel to each other to form a rhomboid; cutting diagonally the assembled strips; 10 and gluing and pressing together the outside parallel edges of the assembled strips.

6. The process of making sounding boards, consisting first, in cutting the boards into strips; second, in cutting strips into proper 15 lengths; third, cutting at an angle the ends of the strips along parallel lines; fourth, in

gluing and assembling the adjacent edges of the strips to form a rhomboid; fifth, in pressing together the adjacent and glued edges of the strips and drying same; sixth, in cutting diagonally across the assembled strips; and seventh, securing the outside parallel edges of the assembled strips together. 20

In testimony whereof I have signed my 25 name to this specification in the presence of two subscribing witnesses.

ALFRED DOLGE.
